UNITED STATES PATENT OFFICE.

RICHARD M. EATON, OF PHILADELPHIA, PENNSYLVANIA, ASSIGNOR TO NOVELTY ELECTRIC COMPANY, OF PHILADELPHIA, PENNSYLVANIA, A CORPORATION OF PENNSYLVANIA.

DESIGN FOR A TELEPHONE-TRANSMITTER BOX.

SPECIFICATION forming part of Design No. 35,266, dated November 5, 1901.

Application filed September 23, 1901. Serial No. 76,301. Term of patent 3½ years.

To all whom it may concern:

Be it known that I, RICHARD M. EATON, a citizen of the United States, residing in Philadelphia, Pennsylvania, have invented and 5 produced a new and original Design for a Telephone-Transmitter Box, of which the following is a specification.

My design for a telephone-transmitter box is fully shown in the accompanying drawings, 10 in which—

Figure 1 is a perspective view thereof. Fig. 2 is a front view, and Fig. 3 is a view of one side.

The essential features of my design consist 15 in a box of rectangular prismatic form A, having a funnel-shaped piece B projecting

from its front surface. From its top surface extends an L-shaped piece C, carrying at its end a convex shell D, the plane including the rear edges of said shell being approximately 20 parallel to the front face of the box A.

I claim as my invention—

The design for a telephone-transmitter box as herein described and as illustrated in the accompanying drawings. 25

In testimony whereof I have signed my name to this specification in the presence of two subscribing witnesses.

RICHARD M. EATON.

Witnesses:

WILLIAM E. BRADLEY,
JOS. H. KLEIN.
